UNITED STATES PATENT OFFICE.

STANLEY H. KNIGHT, OF CHICAGO, ILLINOIS.

SODA FOUNTAIN.

Application filed February 24, 1920. Serial No. 360,643.

To all whom it may concern:

Be it known that I, STANLEY H. KNIGHT, a citizen of the United States of America, and a resident of Chicago, in the county of 5 Cook, State of Illinois, have invented certain new and useful Improvements in Soda Fountains, of which the following is a specification.

This invention relates to that class of soda 10 water fountains in which a main cooling chamber and an auxiliary cooling chamber adapted to contain the fruit juices and other flavors are associated together, with the auxiliary chamber in superimposed and offset 15 relation to the main chamber. And the present improvement has for its object:—

To provide a structural formation and association of the fountain parts whereby the colder water from the bottom of the main 20 cooling chamber is fed upwardly into the auxiliary cooling chamber or chambers to attain an effective and economical cooling of such auxiliary chambers, before such water is discharged into the waste outlet from the 25 fountain, all as will hereinafter more fully appear.

In the accompanying drawings:

Fig. 1, is a longitudinal sectional elevation of a soda fountain structure having the 30 present invention applied.

Fig. 2, is a transverse section on line 2.—2. Fig. 1, of the dispensing portion of the structure.

Fig. 3, is a similar view on line 3.—3. Fig. 35 1 of the work bench portion of the structure.

Like reference numerals indicate like parts in the different views.

Referring to the drawings, 1 designates the main casing of a soda fountain structure 40 having its interior divided into compartments adapted to contain the ice-cream tank, soda water tanks, etc., and broken ice and water, as usual in the present class of soda fountain structure.

45 2 designates a flat top covering the open upper end of the casing 1, and having an entrance opening closed by sliding lids as shown.

3, designates auxiliary cooling casings or 50 sections arranged at the respective sides of the main casing 1 and having communication therewith in the manner hereinafter described. The casings or sections 3 have their lower portions arranged on a plane 55 a short distance below the top portion of the

main casing 1, so that with a normal level of the cooled fluid in said main casing, a comparatively shallow depth of such fluid will prevail in said auxiliary casings or sections 3, to maintain in a properly cooled condition jars of syrup and like soda fountain supplies, usually stored therein.

3' designates a central portion or casing of the structure arranged between the pair of auxiliary casings 3 and above the main 60 casing 1, to provide a supporting and enclosing means for the fountain dispensing faucets 7 and their pipe connections, as shown more particularly in Fig. 1.

In the preferred arrangement shown in 70 the drawings, the present structure is arranged under and behind the dispensing counter of a drug or like store, and the aforesaid casings 3, 3' will preferably have a rear offset formation comprising, an approximately vertical lower wall 4, an intermediate inclined entrance wall 5, and an upper approximately vertical wall 6, as shown more particularly in Figs. 2 and 3.

8 designates pipes or passages connecting 80 the lower ends of the chambers of the outer auxiliary casings 3, with the lower portion of the chamber of the main casing 1, and adapted in a continued operation of the fountain to conduct cold water from the bottom of the chamber of the main casing 1 into the chamber of said auxiliary cooling casings 3 as hereinafter more fully set forth.

9 designate outlet pipes or passages connected to the chambers of the auxiliary 90 chambers 3 intermediate the height of the same and adapted to provide an outflow for excess of liquid in said chambers.

10 designate entrance openings formed, in the inclined entrance walls 5 of the auxiliary casings 3 for the entry and removal from the chambers of the syrup, fruit essence and like supplies stored therein. The entrance opening of the centrally arranged auxiliary casing 3' is adapted for the convenient introduction of the supply of chipped ice with which the cooling chambers of the structure are supplied from time to time, and to such end the open upper portion of the casing 3' is provided with a removable lid or cover 3'.

11 designate work board units of any usual detail construction arranged at the respective ends of the main casing, 1 as shown in Fig. 1.

In the present improvement the normal liquid level in the chamber of the main casting 1 is on a level with the upper end of the outlet pipes or passages 9 above described, 5 and the arrangement is such that with a gradual melting of the ice in said main chamber increase of water takes place in said chamber, and through the pipes or passages 8, in the chambers of the auxiliary 10 casings 3, and rises above the upper end of the outlet pipe or passages 9 to overflow through the same into any convenient and suitable drain connection. By such operation a constant supply of very cold water is 15 maintained in the lower portions of the chambers of the auxiliary casings 3, in an effective and economical manner.

Having thus fully described my said invention what I claim as new and desire to 20 secure by Letters Patent is:—

1. In a soda water fountain, the combination of a lower deep main chamber adapted to contain a cooling medium, soda water tanks and ice cream cans, a superimposed 25 and offset comparatively shallow auxiliary chamber providing a cooling receptacle for fruit juices and the like, the lower portion of the auxiliary chamber extending below the upper portion of the main chamber, a pipe 30 connection between the lower portion of the

main chamber and the bottom of the auxiliary chamber and adapted to convey upwardly the cold water in the lower portion of the main chamber into the bottom of the auxiliary chamber, and an overflow pipe 35 connected to the auxiliary chamber at a point remote from the aforesaid pipe connection.

2. In a soda water fountain the combination of a lower deep main chamber adapted to 40 contain a cooling medium, soda water tanks and ice cream cans, a plurality of superimposed and offset comparatively shallow auxiliary chambers in spaced relation to each other and providing cooling receptacles for fruit juices etc., the lower portions of the auxiliary chambers extending below the upper portion of the main chamber, pipe connections between the lower portion of the main chamber and the bottom portions of 50 the auxiliary chambers and adapted to convey upwardly the cold water from the lower portion of the main chamber into the bottom portion of the auxiliary chambers, and overflow pipes connected to the auxiliary 55 chambers remote from the aforesaid pipe connections.

Signed at Chicago, Illinois, this 21st day of February, 1920.

STANLEY H. KNIGHT.
